UNITED STATES PATENT OFFICE.

GEORGE D. RYTHON, OF CARTHAGE, NEW YORK, ASSIGNOR TO RYTHON & PRINGLE CO., OF CARTHAGE, NEW YORK.

MATERIAL-SHREDDING MACHINE.

Application filed September 2, 1924. Serial No. 735,320.

To all whom it may concern:

Be it known that I, GEORGE D. RYTHON, a citizen of the United States, residing at Carthage, in the county of Jefferson and State of New York, have invented a new and useful Improvement in Material-Shredding Machines, of which the following is a specification.

This invention relates to machines for shredding or reducing the various kinds of pulp, old papers, wood and the like, constituting the "furnish" to the paper making process, to small particles of a size desirable for hydration. The invention relates more particularly to the machines of the class described having the material to be shredded fed by suitable means into a "wobble saw" where the material is reduced to small particles by the saw teeth.

In paper stock shredders heretofore used, the saw arbors could not be quickly and easily disassembled so that the saws could be conditioned at frequent intervals. Considerable difficulty has been experienced with other shredders because the old papers or other stock were cut apart in such manner that the fibers are cut too short and the paper made therewith does not have sufficient strength.

An object of this invention is to provide a paper stock shredder which can be easily and quickly disassembled for conditioning or replacing the saws; also to provide a paper stock shredder which will tear the material apart in proper lengths with little or no cutting action, thus producing a paper which will be very strong; and also to improve paper stock shredders in other respects hereinafter described and set forth in the claims.

Reference is to be had to the accompanying drawings forming part of this specification, in which:

Fig. 1 is a plan view of the paper stock shredder.

Fig. 2 is an elevation of one side thereof.

Fig. 3 is an elevation of the other side of said shredder.

Fig. 4 is a diagrammatic plan view of the driving mechanism for the shredder.

Fig. 5 is a sectional elevation through the shredder on line 5—5, Fig. 2.

Fig. 6 is a longitudinal vertical section through the center of the pulp shredder.

Fig. 7 is a sectional view through the pulp

shredder on the line 5—5, Fig. 2, with the saw arbor inclined and partly disassembled.

Fig. 8 is a sectional view through the shredder on line 8—8, Fig. 5.

Fig. 9 is a sectional view through the shredder on line 9—9, Fig. 5.

Referring to the drawings in detail, 10 indicates a side frame of the machine, and 11 indicates a second side frame thereof, said frames being secured together and spaced 65 apart by a rear spreader 12 and a front spreader 13. These side frames 10 and 11 serve to support the moving parts of the machine. The feed conveyor of the machine may be constructed as follows: The side 70 frames 10 and 11 may be provided with bearings 14 adjacent the rear spreader 12 for rotatably supporting a sprocket shaft 15. A bearing 16 is formed on each side frame between the spreaders 12 and 13, said bearings 75 rotatably supporting a sprocket shaft 17, while a bearing 18 in each side frame rotatably supports the sprocket shaft 19 between the shafts 15 and 17. A series of sprocket wheels 20, 21 and 22 is mounted on 80 the shafts 15, 19 and 17 respectively, each series comprising any desired number of sprocket wheels, and the respective sprocket wheels on each shaft are spaced apart and are in alinement one with the other. Feed 85 chains 23 pass around the three sprocket wheels in alinement on the several shafts, the chains being of a number to correspond to the number of sprocket wheels in each series. Thus, the upper reaches of the feed chains 90 23 constitute a feed apron which is slidably supported on a table 24 extending between the side frames 10 and 11. All of the sprocket wheels on the shafts 17 and 19 are rigidly secured thereto, while only one of 95 the eight sprocket wheels on shaft 15 is secured thereto so that the shaft 15 is rotated from the shaft 17 by the chain on the fixed sprocket wheel, while the other loose sprocket wheels on the shaft 15 allow for 100 any inequalities in the lengths or tensions of the chain. Flat bars 25 are positioned between upper reaches of the chains 23 so that the stock to be shredded is supported as it moves toward the saws on the apron 105 of chains. The rough surface of the apron of chains engages the material and insures that the material is positively conveyed into the shredding mechanism to be described.

110

The driving means for the feed conveyor may be arranged as follows:

26 designates a gear secured to the shaft 19 for positively rotating the shaft, said 5 gear meshing with a pinion 27 secured on a counter-shaft 28. A gear 29 is also secured on the shaft 28 and meshes with a pinion 30 on a second counter-shaft 31. The shaft 28 is journalled in bearings 32 on the 10 side frames 10 and 11, and the shaft 31 is journalled in a bearing 33 secured to the side frame 10. A pulley 34 is secured to the end of the shaft 31 and a belt 35 connects the pulley 34 with a small drive pulley 36 on a saw shaft or arbor 37. A tightener pulley 38 is rotatably mounted on the arm 39 of a bell crank lever pivoted on pin 40, the other arm of said lever being provided with a handle 41 so as to cause the pulley 38 15 to move into and out of engagement with the belt 35, thus starting and stopping the apron of chains as desired.

The machine is also preferably provided with a bed knife. This bed knife 42 is preferably mounted on the spreader 13 adjacent the sprocket wheels 22, and a feed roll 43 is yieldingly and rotatably mounted above the sprocket wheels 22 on the shaft 44. The ends of the shaft 44 are preferably journalled in the ends of the rock arms 45 and 46, the other ends of the arms 45 and 46 being pivotally mounted on a shaft 47 journalled in bearings 48 secured to the side frames 10 and 11. The feed roll 43 is preferably provided with radially disposed flutes or knives 49 which bear on the material to be shredded, causing the material to be flattened into a substantially uniform sheet by the weight of the feed roll 43 and arms 45 and 46, so that the material is delivered in a continuous sheet onto the top of the bed knife 42. The feed roll 43 is positively driven at about the same peripheral speed as the chains 23 by a sprocket wheel 50 on the shaft 44 connected by a chain 51 to a sprocket wheel 52 on the shaft 47. The shaft 47 is continuously rotated by a gear 53 mounted thereon and meshing with a gear 54 on the shaft 15. A tightener spocket 55 on an adjustable arm 56, secured to the arm 46 takes the slack out of the chain and maintains the chain at proper driving tension.

Suitable means are provided for driving the saw arbor 37. In the form shown, the 55 saw arbor 37 is provided with a small section 57 at one end, on which is mounted a fly wheel and pulley 58 which can be connected to any suitable source of power by a belt, not shown, so that said saw arbor is continuously rotated. The pulley 58 is secured on the arbor section in any suitable way, such as by a nut 59 on the threaded end of said arbor section. According to the invention, means are provided for detachably mounting the arbor and saws on the

machine. For this purpose, in the embodiment shown, as bearing case 60 is rotatably mounted on the arbor 37 inwardly beyond the pulley 58, and roller or other bearing races 61 are secured inside said bearing case 70. The bearing case 60 is preferably semi-spherical in shape and is slidably received in a semi-spherical journal formed between a bearing cap 62 and a bearing base 63. Bolts 64 pass through the bearing cap 62, bearing base 63 and into a cored opening 65 in one end of the side frame 11. The heads 66 of the bolts 64 are prevented from upward movement by stop shoulders 67 formed in the opening 65 so that when nuts 68 on the bolts 64 are tightened, the bearing case 60 is rigidly but slidably secured in the semi-spherical journal, thus permitting the arbor 37 and bearing case 60 to be rocked about said bearing case as a pivot to an inclined position as shown in Fig. 7, for purposes to be hereinafter described.

In order to detachably secure the saws on the shaft, in the preferred form shown, a plurality of collars 69 is mounted on the shaft 37 between the bearing case 60 and a similar bearing case 70 near the other end of the shaft. Each of the collars 69 is constrained to rotate with said shaft by a long feather key 71 engaging the collars and the shaft. An annular flange 72 is secured on a threaded section 73 of said shaft near the bearing 60 and one end of each of a plurality of rods 74 is seated in said flange and passes through each of the collars 69 at a distance from the center of the shaft 37. The opposite ends of the rods 74 are seated in an end collar 75 so that the rods are prevented from axial movement. Each of the collars 69 has one face perpendicular to its axis, and the other face inclined to the axis of the collar and arbor, the collars being so arranged on the shaft 37 that perpendicular faces of adjacent collars abut. A large diameter saw 76 is positioned between the perpendicular faces of each pair of abutting collars and a saw 77, of smaller diameter is positioned between the inclined faces of abutting collars so that the saws are alternately perpendicular and inclined to the axis of the shaft 37. Each of the collars 69 has an annular shoulder 78, and the internal diameter of each saw is fitted to the periphery of this shoulder 78 so as to position each saw concentric with the shaft 37. Each saw is provided with a plurality of holes through which the rods 74 pass so that the rotation of said saws relative to the shaft 37 is prevented. A sleeve 79 is mounted on the end 80 of the shaft 37, said end being smaller in diameter than the main body 81 of the shaft, and also being threaded on its end to receive a nut 82. The pulley 36 is mounted on the shaft section 80 between the nut 82 and sleeve 79, and when

said nut is tightened, an enlarged annular shoulder 84 on said sleeve bears against the collar 75 and presses all of the collars and saws into one rigid rotating unit.

- 5 The bearing case 70 is preferably, but not necessarily, semi-spherical in shape and a roller or other bearing race 85 is mounted in said bearing case 70 on the sleeve 79 so that said sleeve may move axially of the bearing 10 race 85 when the nut 82 is tightened. Packing plates 70^a are provided outside the bearing cases 60 and 70 so that said cases may be packed with grease for the lubrication of the roller bearings. The bearing case 70 is supported on a bearing base 86, and a bearing cap 87 with bolts 88 hold the bearing case 15 70 in much the same manner as the bearing case 60 on the other end of the shaft 37. A plurality of notches 89 is provided in the 20 bed knife 42, each notch being adapted to permit the rotation of the large diameter saws 76, while the inclined or "wobble saws" which are smaller diameters, clear the bed knife between the notches 89. By adjusting 25 the flange 72 on the threaded section 73, the proper location of the saws 76 relative to the notches 89 is obtained. As a result of the arrangement of the saws relative to the bed knife 42, the paper stock is first ripped into 30 ribbons without any cutting action whatever. The stock which is fed to the arbor by the feeding mechanism is supported on the bed knife 42 as it approaches the saws in such a way that the grooves 89 form open spaces 35 over which the stock has to bridge. The teeth in the saws 76 then engage the stock in this bridged position and tear out a series of pieces of stock, this tearing action being very violent, so that the edges are very 40 rough and ragged because the stock is tough and unsupported over the grooves 89. The ribbon which is produced by the saws 76 is then treated by the "wobble saws" 77 which run very close to the bed knife 42 so that 45 the ribbons are further torn apart and thoroughly disintegrated to form paper pulp, which makes a very strong and tough paper. The pulp is delivered from the front of the machine down a chute 90, preferably as a 50 part of the front spreader 13.

In order to prevent the paper pulp from being scattered by the rapidly rotating saw arbor, there is provided a hood 91, semi-cylindrical in shape, and which is secured to 55 hood end castings 92, which in turn are supported by cheek castings 93. The cheek castings 93 are held in position by dowel pins 94 engaging the spreader 13 and are provided with lugs 95 adapted to be engaged 60 by the hooks 96 of the fastening bolts 97. The upper end of the bolts 97 is secured by nuts 98 to brackets 99 on the hood ends 92 so that the hood can be quickly disassembled 65 by loosening the nuts 98, turning the hooks 96 through 90° to be free of the lugs 95 and

lifting the hood, hood ends 92 and cheek castings 93 from their position on the machine. The bearing cap 87, nut 82, pulley 36 sleeve 79, collar 75, saws 76 and 77, and collars 69 are then removed in the order named, 70 preferably after blocking up the shaft 37 in an inclined position, shown in Fig. 7. Adjusting bolts 100 are mounted in the side frames 10 and 11 to properly position the bearing bases 86 and 63 relatively to said side frames. This renders possible removal, repair and replacement of any of the saws in a very short space of time by demounting 75 one end of the shaft only, as hereinabove described, and the construction and form of 80 the frame and other parts of the machine provide economy of space before and after the machine is set up, and facilitate the operation of setting up or assembling the machine. 85

I claim as my invention:—

1. In a material shredding machine, a rotatable saw arbor, a plurality of circular saws mounted on said arbor, bearings rotatably supporting each end of said saw arbor, 90 means for changing the angular position of the axis of said arbor about one of said bearings for disassembly of said saws, and means for feeding the material to be shredded into said saws. 95

2. In a material shredding machine, an arbor, a plurality of spacing collars mounted on said arbor, a plurality of tools supported on said arbor by said collars, 100 means for rotating said arbor, means for feeding the material to be shredded to said tools, means for rotatably supporting each end of said arbor and for permitting the detachment of one end of said arbor from its bearing, and inclining the axis of the 105 arbor from its normal operating position so that said tools and collars may be removed from said arbor.

3. In a material shredding machine, a rotatable arbor, a plurality of tools detachably mounted on said arbor, bearings 110 rotatably supporting the ends of said saw arbor, means for releasably securing said bearings in predetermined substantially fixed positions, said means permitting either end of said arbor to be shifted to remove either end of the arbor and its bearing from said securing means while the other end remains secured by said securing means to permit removal of said tools from the arbor. 115

4. In a material shredding machine, a saw arbor, a plurality of circular saws mounted in spaced relation on said arbor substantially perpendicular to the axis of said arbor, a plurality of circular wobble saws mounted on said arbor, said wobble saws being disposed between said perpendicular saws and being inclined to the axis of the arbor and having a diameter smaller than 125 said perpendicular saws, a bed knife having 130

- notches adapted to receive the peripheries of the perpendicular saws, means for rotating said arbor, and means for feeding the material to be shredded into said saws.
5. In a material shredding machine, a saw arbor, a plurality of circular saws mounted in spaced relation on said arbor substantially perpendicular to the axis of said arbor, a plurality of circular wabble saws mounted
- 10 on said arbor, said wabble saws being disposed between said perpendicular saws and being inclined to the axis of the arbor and having a diameter smaller than said perpendicular saws, means for detachably mounting
- 15 said saws on said arbor, a bed knife having a plurality of spaced notches adapted to receive portions of the peripheries of said perpendicular saws, and means for rotating said arbor.
- 20 6. In a material shredding machine, a rotatable saw arbor, a plurality of circular saws in spaced relation on said arbor substantially perpendicular to the axis of said arbor, a plurality of circular wabble saws on
- 25 said arbor, said wabble saws being disposed between said perpendicular saws, bearings rotatably supporting the ends of said arbor, means for releasably securing said bearings in predetermined substantially fixed positions, said means permitting either end of
- 30 said arbor to be shifted to remove either end of said arbor and its bearing from said securing means while the other end remains secured by said securing means to permit
- 35 removal of said saws from said arbor.
7. In a material shredding machine, a rotatable saw arbor, a plurality of circular saws in spaced relation on said arbor substantially perpendicular to the axis of said arbor, a plurality of circular wabble saws on
- 40 said arbor, said wabble saws being disposed between said perpendicular saws, bearings rotatably supporting the ends of said arbor, means for releasably securing
- 45 said bearings in predetermined substantially fixed positions, said means permitting either end of said arbor to be shifted to remove either end of said arbor and its bearings from said securing means while the other end remains secured by said securing means
- 50 to permit removal of said saws from said arbor, a bed knife adjacent said arbor, said bed knife having notches adapted to receive portions of the peripheries of said perpendicular saws and portions adjacent said
- 55 notches for supporting the material to be shredded as it extends across said notched portions to be acted upon by said perpendicular saws.
- 60 8. In a material shredding machine, a frame, a rotatable saw arbor, a plurality of saws detachably mounted on said arbor, bearings rotatably supporting the ends of said arbor, bearing cases for said bearings, said bearing cases having arcuate shaped
- outer sides, means for releasably securing said bearing cases to the frame of the machine, said means permitting one end of said arbor to be released and the arbor to pivot on the bearing case at the other end of the arbor to permit removal of said saws without dismantling the machine.
9. In a material shredding machine, a rotatable saw arbor, a plurality of circular saws mounted in spaced relation on said arbor substantially perpendicular to the axis of said arbor, a plurality of saws mounted on said arbor between said first named saws and inclined to said first named saws, a bed knife adjacent said saws and having notches to receive portions of the peripheries of said first named saws, and conveying means for feeding the material to be operated upon onto said bed knife.
10. In a material shredding machine, a rotatable saw arbor, a plurality of circular saws mounted in spaced relation on said arbor substantially perpendicular to the axis of said arbor, a plurality of saws mounted on said arbor between said first named saws and inclined to said first named saws, a bed knife adjacent said saws and having notches to receive portions of the peripheries of said first named saws, conveying means for feeding the material to be operated upon onto said bed knife, and means cooperating with said conveying means for compressing the material as it is fed onto said bed knife.
11. In a material shredding machine, a saw arbor, a plurality of spacing collars secured to said arbor, a plurality of circular saws mounted on said arbor between said spacing collars, a bearing rotatably supporting each end of said arbor, one of said bearings having a semi-spherical supporting member, means for rotating said arbor, means for feeding material to be shredded into said arbor, and means for mounting said supporting member to permit inclination of the axis of said arbor about said semi-spherical supporting member from its normal operating position so as to permit detachment of the spacing collars and saws.
12. In a material shredding machine, a saw arbor, a plurality of circular saws mounted on said arbor, a spacing collar between each pair of saws, a sleeve mounted on one end of said arbor, a nut on said arbor adapted to bear against said sleeve and force the saws and collars into engagement, a bearing rotatably receiving said sleeve, a second bearing rotatably receiving the other end of said arbor, means for rotating said arbor and saws, and means for feeding the material to be shredded into said saws.
13. In a material shredding machine, a saw arbor, a plurality of frame members, a

semi-spherical bearing member mounted on one of said frame members, a removable bearing member associated with another of said frame members, said bearing members being adapted to rotatably support said saw arbor, means for rotating said saw arbor, means for feeding material to be shredded into said saws, means for detachably securing said removable bearing member on said frame, said means permitting the removal of the removable bearing member from said saw arbor so that said arbor may be inclined from its normal operating position about said semi-spherical bearing member.

14. In a material shredding machine, a saw arbor, a plurality of circular saws detachably mounted on said arbor, a semi-spherical bearing member rotatably supporting each end of said arbor, means for rotating said saw arbor, means for feeding material to be shredded into said saws, and means for removably mounting one of said bearing members on said machine, said means permitting said bearing member to be detached from its mounting so that the saw arbor may be inclined from its normal operating position to permit removal of said saws from the arbor.

15. In a material shredding machine, a saw arbor, a plurality of circular saws mounted on said arbor, a hood member partially enclosing said saws, a plurality of

frame supporting members including a plurality of hood supporting portions, hook bolts removably securing said hood member to said hood supporting members, means for rotating said saw arbor, and means for feeding material to be shredded into said saws.

16. In a material shredding machine, a rotatable shaft, a plurality of rotatable saws disposed at substantially right angles to the axis of said shaft, a plurality of saws of smaller diameter than said first named saws and disposed at inclinations to said first named saws around said shaft, the relatively large and small diameter saws being arranged in substantial alternation, means for supporting a portion of material to be shredded adjacent said saws, said means comprising alined substantially alternate material supporting and non-supporting portions adjacent said saws, the non-supporting portions being alined with the peripheries of the large diameter saws and the supporting portions being alined with the small diameter saws, whereby the portions of the material to be shredded are engaged by the large diameter saws in the non-supporting portions of said material supporting means to remove portions of the material and by the small diameter saws at the edges of said supporting portions adjacent said small diameter saws.

GEO. D. RYTHER.
